FRANCIS JOHN GEORGE BRUCE WATSON, OF ISLINGTON, LONDON, EDWARD CULVER, OF CROUCH END, LONDON, AND ALFRED HENRY EMERSON, OF FINCHLEY, LONDON, ENGLAND, ASSIGNORS TO UNITED KINGDOM OPTICAL COMPANY, LIMITED, OF LONDON, ENGLAND

METHOD OF MANUFACTURING LENSES AND APPARATUS THEREFOR

Application filed November 24, 1928. Serial No. 321,602.

Our invention relates to an apparatus and method of manufacturing lenses.

In particular it is our object to provide a method of manufacturing bifocal lenses with a minimum of loss, by reason of the presence of air bubbles, reflecting surfaces, warping and the like.

It is a further object to provide a method and means of fusing parts of the button together and of fusing the buttons to countersinks, so that parts used for this purpose will not bring about warping, twisting or displacement of the parts one to the other, so that the feelers and the means used for maintaining the feelers in position will disappear and whatever parts are remaining can be eliminated in the finished product by grinding.

The invention with its various novel features is illustrated in the accompanying drawings with reference to which it will now be described.

Referring to the drawings,

Figure 1 is a plan view of a plurality of unfused buttons ready for introduction into the furnace to be fused,

Figure 2 is a section on the line 2—2 of Figure 1 looking in the direction of the arrows,

Figure 3 is a top plan view of a countersink with an unfused button in position,

Figure 4 is a section (enlarged) on the line 4—4 of Figure 3,

Figure 5 is a side elevation of one of the crown strips or sections of the button showing its grey edge,

Figure 6 is a top plan view of the fused countersink and button after grinding,

Figure 7 is a detail perspective of the small feeler enlarged,

Figure 8 is a section through the countersink in its final fused condition on the line 4—4 after fusing and grinding,

Figure 9 is an enlarged detail section showing the application of adhesive and feelers to the button and countersink.

Referring to the drawings in detail, 1 is the bottom of a trough-like tray having side walls 2. This tray is of metal. On the bottom of the tray is located a strip of asbestos

3. Between the side walls of the tray and upon this asbestos strip 3 we locate groups of flint and crown glass pieces or strips which when fused and trimmed round constitute a button. These groups can be in single or double rows with spring pressure in centre or on one side. The crown strips are designated 4 and the flint intermediate strip is designated 5.

This strip 5 later becomes the fused zonal insert that appears in the final lens as a part of the countersink 6 (see Figure 6). These groups of strips to form the buttons are oppositely disposed to one another and are spring pressed outwardly or otherwise positioned by the spring 7.

The metal tray composed of the parts 1 and 2 carrying the strips to be fused is then placed in a furnace where it is heated for an appreciable period of time of approximately 15 minutes at approximately 650° C. temperature. Upon being withdrawn the fused square buttons are removed and trimmed to circular form as in Figure 3, the edges appearing as at 9. The undersurface of the button is ground to a convex shape indicated at 10, corresponding to the concave portion 11 of the countersink. (It will be understood that the under surface of the button might be concave corresponding to a convex surface of the countersink). The button is so positioned above the countersink concavity 11 that when heated it will drop down without warping and twisting and will be completely fused without bubbles, or other defects, which would impair the value of the resulting lens.

To accomplish this we utilize thin feelers 12 of zinc or other soft metal. Instead of metal feelers there may be employed feelers formed of suitable metal oxides, or powder mixed with gum or other material adapted to collapse at a predetermined temperature. We locate the feelers preferably as indicated so that one edge of the button rests upon the end of the concavity of the countersink, while the other edges of the button are suspended above the countersink by the feelers 12 for a purpose hereinafter described.

In order to position these feelers and main-

tain them in proper position with respect to the button and the countersink, we use a cement. The feelers are touched with cement as well as the opposite edges of the button, the cement being designated as 13. 5 This serves to cement the feelers to the countersink and buttons so as to hold the several parts in position. While the cement is drying, we employ a spring 14 to hold the parts in position. When the cement is dry, 10 this spring is removed and the countersink with its button can be easily handled.

The countersink and button, which are not yet fused, may then be placed on a suitable 15 carborundum slab in the usual way in the metal trough having the bottom 1 and side walls 2 and again inserted in the furnace. The temperature is then raised to 750° C. approximately for about 15 minutes approximately. Our object is to permit of a 20 progressive fusing of the button from the point where it touches the countersink in the direction of the feelers, so as to exclude the air beneath the button and between it and the 25 countersink, so that there will be no air bubbles caught between the button and the countersink.

The temperature is then allowed to fall 30 gradually for annealing purposes. This is a very important step in connection with the manufacture of this type of lens which we have found to be especially adaptable to its 35 peculiar requirements.

Where the depression curve 11 is very deep 35 we may use feelers made of harder metal.

We prefer that the inside side walls 15 of the crown segments or strips 4 to have a partly finished or grey edge 15 as this prevents reflection from this edge in the final 40 lens.

It will be understood that we desire to comprehend within our invention all the modifications necessary to adapt it to varying conditions and uses.

45 What we claim is:—

1. In an apparatus for fusing countersinks, a metallic trough, a strip of inert material on the bottom of the trough such as asbestos, and yielding means adapted to be interposed between groups of pieces of glass to be fused into buttons, to force yieldingly said groups outwardly across the side walls of the trough.

2. In the art of manufacturing fused lenses, a new article of manufacture for carrying lenses during fusing, consisting of a trough of metal having side walls, a strip of material on the bottom thereof, upon which the lenses rest and which is not affected by the heat of the furnace, and yielding means for 55 maintaining the lenses against the side walls to accommodate the expansion and contraction of the parts while at the same time maintaining the lenses in a predetermined position.

3. In combination in the manufacture of a 60 lens, a countersink, a button, soft metal feelers

interposed therebetween, and cement applied to said feelers for engagement with the button and countersink.

4. In combination in the manufacture of a lens, a countersink, a button, and fusible 70 metal feelers positioned and adapted to hold the button out of contact with the countersink except at one place.

In testimony that we claim the foregoing as our invention we have signed our names 75 this 24th day of October, 1928.

FRANCIS JOHN GEORGE BRUCE WATSON.

EDWARD CULVER.

ALFRED HENRY EMERSON.
